(57) **CLAIM**

The ornamental design for the suction ring for ophthalmic laser surgery, as shown and described.

DESCRIPTION

FIG. 1 is a top plan view of a suction ring for ophthalmic laser surgery showing my new design;

FIG. 2 is a bottom plan view thereof;

FIG. 3 is a left side elevational view thereof;

FIG. 4 is a front elevational view thereof;

FIG. 5 is a rear elevational view thereof; and,

FIG. 6 is a left rear perspective view of the suction ring for ophthalmic laser surgery showing my new design.
